REMOTE CONTROL SYSTEM

Paul H. Crago, Wilkinsburg, Pa., assignor to The Union Switch & Signal Company, Swissvale, Pa., a corporation of Pennsylvania

Application April 16, 1938, Serial No. 202,507

29 Claims.

(Cl. 246—3)

My invention relates to remote control systems, and particularly to remote control systems for controlling railway track switches and signals from a remote office station and for indicating at the office station the condition of the track switches and signals and other information, such as the presence of a train in the vicinity of a track switch.

A feature of my invention is the provision in systems of the type here contemplated of a pilot circuit extending between an office station and a remote field station for operating apparatus at each of the two stations in synchronism. A further feature of my invention is the provision of novel and improved apparatus that permits, by the use of code following contact members, the transmitting of different control influences from an office station to a remote field station and the returning of different indication influences to the office station over a line circuit comprising a single line wire and a common return wire. By the use of such code following contact members, one at each station, it is possible to apply control and indication influences alternately to the opposite ends of the line circuit so spaced in time relation that overlapping of the impulses is avoided. Still another feature of my invention is the provision of novel and improved apparatus that permits by the use of a pilot line circuit the transmission of four different indications over a single two-wire line circuit, at least three of which indications are entirely independent of each other and may be displayed in any combination. Other features and advantages of my invention will appear as the specification progresses.

I shall describe three forms of apparatus embodying my invention, and shall then point out the novel features thereof in claims.

In the accompanying drawings, Figs. 1a and 1b, when taken together with Fig. 1a placed at the left of Fig. 1b, are a diagrammatic view of one form of apparatus embodying my invention when applied to the control of a railway track switch and its related signals from an office station and to the indicating at the office station of the positions of the track switch and signals, and also the occupancy of track sections in the vicinity of the track switch. Figs. 2a and 2b, when taken together with Fig. 2a placed at the left of Fig. 2b, are a diagrammatic view of a second form of apparatus embodying my invention when applied to the control of a railway track switch and its related signals and to the indicating of the positions of the switch and sig-

nals and the occupancy of track sections in the vicinity of the switch. Fig. 3 is a diagrammatic view of a third form of apparatus embodying my invention when applied to the control of a track switch and its related signals and to indicating their positions and the occupancy of the associated track sections. In each of the different views, like reference characters designate similar parts.

It will be understood that my invention is not limited to the control and indication of railway track switches, signals and occupancy of track sections. This one application of the invention will serve, however, to illustrate the many places where the invention may be used.

To simplify the drawings in order that they may be more readily understood, I have in many instances illustrated relay contact fingers remote from the relay windings which operate them. In all such instances, the reference character of the corresponding relay is placed adjacent the contact finger, and the finger is shown in the position corresponding to the normal energized or deenergized condition of the relay winding. In several instances I have also shown circuit controlling contacts remote from the devices which operate them. Such contacts are identified by placing the reference character of the associated device adjacent the contact, and by the contact being shown in the position corresponding to the normal position of the device. Furthermore, in the following description current of positive polarity will at times be referred to as current of normal polarity, and current of negative polarity will at times be referred to as current of reverse polarity.

Referring to Figs. 1a and 1b, the reference characters 11a and 11b designate the track rails of a stretch of railway track which are formed by the usual insulated rail joints into track sections 1T, 2T and 3T, a track switch SW being located in track section 2T. Each of these track sections is provided with a track circuit comprising a current source, such as a battery 2, connected across the rails at one end of the section and a track relay designated R plus a prefix corresponding to the section connected across the rails at the other end of the section.

Two signals RA and RB govern eastbound traffic, that is, traffic moving from left to right in Fig. 1b, through the track section 2T and over the track switch SW, the two signals being mounted on the same mast. Two signals LA and LB govern westbound traffic, that is, traffic moving from right to left in Fig. 1b, through the

track section 2T and over the switch SW. These signals may be of any suitable type and are shown conventionally. It will be understood, of course, that other signals governing traffic approaching 5 the signals RA, RB, LA and LB would be provided in accordance with standard practice, but these other signals are not shown since they are not required to illustrate my invention. The track switch SW is moved to its normal and reverse positions through the medium of a power operated switch mechanism SM, which may be of any standard type.

The track switch SW and its related signals are controlled through the medium of apparatus placed partly at a field station FS located adjacent the switch SW and partly at a remote office station DS, such as a dispatcher's office. The apparatuses at the two stations are interrelated by virtue of line circuits extending between the two stations, and which line circuits will be more fully described hereinafter. The two stations FS and DS are equipped with proper sources of current, such as a battery 16 at the station FS and a battery 17 at the station DS. 20 These two batteries 16 and 17 are each provided with a positive terminal B, a negative terminal N, and a center or common terminal C, the terminal C being connected with a common return line wire designated by the reference character CL, and which line wire serves as a common side for the above-mentioned line circuits.

Referring first to the apparatus at the field station FS, the operating circuits for each signal are governed by a signal control relay designated 35 by the reference character H plus a prefix corresponding to the signal. The operating circuits for each signal are those of standard practice, and are not shown for the sake of simplicity. It is deemed sufficient for this application to point 40 out that when a signal control relay is deenergized the associated signal is set to display a stop indication, and when the relay is energized the signal is set to display a proceed indication. For example, when the signal control relay RAH for 45 signal RA is deenergized, the signal RA is operated to its stop position, and when the relay RAH is energized the signal RA is operated to a proceed position.

The signal control relays are in turn governed 50 by two remote control relays LGR and RGR, to be described later, as well as by traffic conditions and the position of the track switch SW. The control of the signal control relays by traffic conditions is illustrated conventionally by traffic 55 controlled networks 72 and 75 since such control is not involved in my present invention, and it may be that shown and described in my copending application for United States Letters Patent, Serial No. 631,041, filed August 30, 1932, for 60 Remote control system, now Patent No. 2,124,651. The relays RAH and RBH are selectively governed over a circuit comprising the traffic controlled circuit network 72, front contact 73 of control relay RGR, back contact 74 of control relay LGR and a contact SW1 operated by the track switch SW, the relay RAH being selected when the switch SW is set at its normal position and the contact SW1 occupies the full line position, and the relay RBH being selected when the 65 switch is set at its reverse position and the contact SW1 occupies the dotted line position. In a similar fashion, the signal control relays LAH and LBH are selectively governed over a circuit comprising the traffic controlled circuit network 75, back contact 76 of relay RGR, front contact

77 of relay LGR and a contact SW2 operated by the track switch, the relay LAH being selected when the switch is normal so that the contact SW2 occupies the solid line position and the relay LBH being selected when the switch is in its reverse position so that the contact SW2 occupies the dotted line position. Consequently, when the control relay RGR is picked up and the control relay LGR is released, in a manner to be later described, the signal control relay RAH or RBH is energized according to the position of the track switch, it being assumed, of course, that the traffic controlled circuit network 72 is also closed. Again, when the control relay LGR is picked up and the control relay RGR is released, the relay LAH or LBH is selected according to the position of the track switch, the traffic controlled network 75 being assumed to be closed.

Two approach locking relays RMR and LMR, a repeater relay MP and a time element relay TE are provided in the field station apparatus of Fig. 1b for governing, as is the custom in systems of this character, the operation of the switch and signals. The approach locking relays RMR and LMR are normally energized over traffic controlled networks of any standard form responsive to traffic approaching the switch SW and which networks are here indicated by reference characters 3 and 6. One form of traffic controlled network that may be used is that shown in my aforementioned application Serial No. 631,041. As illustrated, the relay RMR is normally energized by a circuit extending from terminal B of battery 16 over back contacts 4 and 5 of relays RBH and RAH, respectively, network 3, winding of relay RMR and battery terminal C. In a like manner, the relay LMR is energized over a circuit extending from battery terminal B, back contacts 7 and 8 of relays LBH and LAH, respectively, network 6, winding of relay LMR and terminal C. In shunt with the network 3 is a front contact 217 of the time element relay TE, and another front contact 218 of relay TE is disposed in shunt with network 6. It follows that when signal control relay RAH or RBH is picked up to operate the corresponding signal the locking relay RMR is deenergized and if relay RBH or RAH is subsequently released while the network 3 is opened in response to traffic conditions, the relay RMR can be reenergized by operation of relay TE to close front contact 217. In like fashion, the locking relay LMR can be reenergized while the network 6 is open in response to traffic conditions by operation of relay TE to close front contact 218. The time element relay TE is of the usual type which requires its winding to be energized a selected period of time, for example, one minute, before its front contacts 217 and 218 are closed. The repeater relay MP is controlled by a circuit having two branch paths, one path of which includes front contact 220 of relay LMR and back contacts 219, 5 and 4 of relays RMR, RAH and RBH, respectively; and the other path involves back contacts 223, 8 and 7 of relays LMR, LAH and LBH, respectively. The relay MP controls at its front contact 221 the operation of the time element relay TE.

The immediate control of the switch mechanism SM is accomplished by a polarized switch controlling relay WR. The operating circuits governed by relay WR for reversibly operating the mechanism SM are not shown since these circuits are not required for an understanding of my present invention. Although the operating circuits controlled by relay WR may be any one

of the forms in present day use, they would be preferably those disclosed in my aforementioned application Serial No. 631,041, to which reference is made for a full understanding of such switch operating circuits. It is sufficient in the instant case to say that when relay WR is energized with current of positive or normal polarity the mechanism SM is operated to move the switch to its normal position, that is, the position illustrated in Fig. 1b. When relay WR is energized with current of negative or reverse polarity, the mechanism SM is operated to move the track switch to its reverse position, that is, the position opposite that illustrated in Fig. 1b. The relay WR is normally deenergized, is energized only during a movement of the switch, and is provided with slow release characteristics.

The relay WR is in turn controlled by the remote control relays LGR and RGR over circuit networks preferably similar to those disclosed and described in my copending application Serial No. 631,041, and which networks are designated conventionally in Fig. 1b by the reference characters 10 and 11. It should be pointed out that when both control relays LGR and RGR are picked up the relay WR is supplied with current opposite in polarity from that by which the relay was last energized. For example, with the switch SW in its normal position, the relay WR was last energized by current of normal polarity, and thus if the relays LGR and RGR are both picked up, closing their respective front contacts 13 and 12, a circuit is formed from the negative terminal N over circuit network 11, front contacts 12 and 13, winding of relay WR and terminal C, and the relay WR is energized by current of negative or reverse polarity. In response to an operation of the switch to the reverse position, the network 10 is prepared and the network 11 is opened, the relays LGR and RGR being released before network 10 is closed. The next operation of relays RGR and LGR to close their respective front contacts 12 and 13 completes a circuit from the positive terminal B of the current source over network 10, front contacts 12 and 13, winding of relay WR and terminal C, and the relay WR is supplied with current of positive or normal polarity.

A switch indication relay KR is controlled over a pole changer 14 which is operatively connected with the mechanism SM and the switch SW, as indicated by a dash line 15, the arrangement being such that relay KR is energized by current of normal polarity when the switch is in its normal position and is energized by current of reverse polarity when the switch is moved to its reverse position. The relay KR is also preferably governed by the control relays RGR and LGR in the manner described in my aforementioned application Serial No. 631,041, and which control is here indicated by contact 109, the arrangement being such that when relays RGR and LGR are both picked up the contact 109 is open and relay KR is released.

Before describing the apparatus at the office station DS, I shall point out the pilot line circuit extending between the two stations, and which pilot line circuit forms an essential element of my present invention. In Figs. 1a and 1b this pilot line circuit serially includes the windings of two code following relays 1CF and 2CF, the relay 1CF being located at the office station and the relay 2CF being located at the field station. This pilot line circuit can be traced from the B terminal of the battery 17 at the office station

over code contact member 18 and contact 19 of a code transmitter DC, winding 20 of relay 1CF, line wire PL to station FS, winding 21 of relay 2CF, and the common return wire CL back to the terminal C of battery 17. The type of code transmitter DC is immaterial and, as here shown, its contact member 18 is operated between the full line position and the dotted line position at a predetermined rate of, say, for example, 120 times per minute when the winding 22 of the code transmitter is energized. In Fig. 1a, the winding 22 of the code transmitter DC is connected across the terminals B and C of the current source and is continually active, so that the pilot line circuit is periodically opened and closed at the predetermined rate here assumed as 120 times per minute. It follows that the two code following relays 1CF and 2CF are operated in synchronism so that when the pilot circuit is closed the contact members 23, 24 and 25 of relay 1CF and the contact members 26, 27 and 28 of relay 2CF are actuated to engage their respective front or first position contacts, and when the pilot circuit is open these contact members of relays 1CF and 2CF are actuated to engage their respective back 25 or second position contacts. The manner of using this synchronous operation of the contact members of the code following relays 1CF and 2CF will appear as the specification progresses.

Two other line circuits extend between the stations DS and FS. One of these line circuits is a control and indication circuit which has a line wire 29 as one side of the circuit and is completed over the common return wire CL as the other side of the circuit. The other line circuit 35 is an indication circuit which includes the line wire 30 extending between the two stations and is completed over the common return wire CL.

Referring now to the control and indication line circuit and looking at the field station FS, this control and indication circuit terminates in two parallel loop circuits and is associated with certain track switch and signal indication circuits. The remote control relays LGR and RGR are interposed one in each of the parallel loop 45 circuits. Starting from the terminal 44, at which the line wire 29 is terminated at station FS, one loop circuit extends over front contact 78 of track relay 2TR, back contact 79 of relay WR, front contact 45 of relay RMR, winding 46 of relay LGR, asymmetric unit 47, and to the common return wire CL. The second loop circuit is the same up to back contact 79, and thence over front contact 48 of relay LMR, winding 49 of relay RGR, asymmetric unit 50 and the common return wire CL. The units 47 and 50 are disposed reverse to each other, the unit 47 being disposed with its conducting or low resistance direction away from the common line wire, and the unit 50 being disposed with its conducting direction toward the common line wire. Consequently, when the potential of the terminal 44 is positive with respect to the common line wire, current flows through the asymmetric unit 50 and the relay RGR is energized; when the potential of the terminal 44 is negative with respect to the common line wire, current flows through the asymmetric unit 47 and the relay LGR is energized; and when the potential of the terminal 44 with respect to the common line wire is alternately 70 positive and negative, then relays LGR and RGR are both energized. The winding 46 of relay LGR is shunted by an asymmetric unit 51, and the winding 49 of relay RGR is shunted by an asymmetric unit 52, so that these relays are slow 75

releasing in character. The parts are so proportioned that when either relay LGR or RGR is energized by impulses of current of a frequency of 120 times per minute, that is, the operating frequency of the pilot line circuit, the relay remains picked up from one impulse until the next. The circuits at the field station associated with the control and indication line circuit for indicating the positions of the track switch and signals will be taken up and explained when the operation of the apparatus is described.

At the office station, the control and indication line circuit terminates in two parallel loop circuits and is associated with certain control 15 and indicating circuits. Starting from a terminal 87, at which the line wire 29 is terminated at the office station DS, one loop circuit includes the respective back contacts 88 and 89 of relays RWE and NWE to be referred to later, wire 53, 20 back contact 54 of a relay PBR to be referred to later, asymmetric unit 55, winding 56 of an indication relay RKP to be later described, and to the common return wire CL. The other loop circuit is the same up to back contact 54, thence 25 over asymmetric unit 57, winding 58 of an indication relay LKP to be referred to, and to the common return wire CL. The asymmetric units 55 and 57 are disposed reverse to each other, the unit 55 being disposed with its conducting 30 direction toward the common wire CL, and the unit 57 being disposed with its conducting direction away from the common wire. Hence, when the potential of terminal 87 is positive with respect to the common wire, current flows through the unit 55 and the relay RKP is energized, and, when the potential of the terminal 87 is negative with respect to the common wire, current flows through the unit 57 and the relay LKP is energized. The relays LKP and RKP are each provided 35 with slow release characteristics by virtue of an asymmetric unit 59 connected across the winding of relay RKP and an asymmetric unit 60 connected across the winding of relay LKP. The parts are so proportioned that, when the relays LKP and RKP are energized by current 40 impulses of the code frequency rate of 120 times per minute, the relays remain picked up from one impulse until the next. The control and indicating circuits at the office station associated with 45 the control and indication line circuit will be referred to later.

Referring next to the apparatus at the office station DS, a signal control lever LV and a switch control push button PB are mounted for convenient manual operation. The lever LV is normally positioned at a mid position *n*, as illustrated, and is operable to either a left-hand position *l* or to a right-hand position *r*. Five circuit controlling contact members 31, 34, 97, 98 and 50 101 are operatively connected with the lever LV for closing contacts at different positions of the lever. The push button PB is of the spring return type and governs a relay PBR. In the normal position of the push button, the winding 37 of relay PBR is short-circuited over the contact 55 98 of the push button and the relay is deenergized, but when the push button is depressed the short circuit is removed and a circuit is formed for energizing the relay. This circuit involves 60 terminal B, back contacts 39, 40 and 41 of the relays LKP, RKP and OS, respectively, winding 37, contact 42 of push button PB, resistance 43 and to the terminal C.

Three signal indication lamps 61, 62 and 63 65 are mounted preferably adjacent the signal lever

LV to indicate the position of the signals at the track switch SW, the lamp 61 being illuminated to indicate the stop position of the signals, the lamp 63 being illuminated to indicate a proceed position of either signal RA or RB, and the lamp 62 being illuminated to indicate a proceed position of either signal LA or LB. As will later appear, the lamp 64 also serves to indicate when the time element relay TE at the field station has operated. As here shown, these lamps are controlled by the two indication relays LKP and RKP, the circuit for lamp 61 serially including back contacts 64 and 65 of relays LKP and RKP, respectively; the circuit for lamp 62 including front contact 66 of relay RKP, lamp 62, controller contact 97-98 of lever LV and a front contact 67 of relay LKP; and the circuit for lamp 63 including front contact 68 of relay LKP, lamp 63, controller contact 98-100 of lever LV, and front contact 69 of relay RKP.

To indicate the normal and reverse positions of the track switch SW, the office station apparatus is provided with a normal switch indication relay NWE and a lamp 68, and a reverse switch indication relay RWE and a lamp 70. 25 The relays NWE and RWE and their respective lamps 68 and 70 are controlled in part by the indication relays LKP and RKP. At such time as the relay PBR is released and the indication relay RKP is picked up, the relay NWE is energized by virtue of a pick-up circuit extending from terminal B over back contact 89 of relay PBR, front contact 81 of relay RKP, back contact 82 of relay RWE, winding 69 of relay NWE and to the terminal C. With relay NWE thus picked up, a stick circuit is formed over its front contact 83 which shunts around the front contact 81 of relay RKP, so that the relay NWE is retained energized subsequent to the release of the indication relay RKP. The lamp 68 is connected 30 in multiple with the winding 69 of relay NWE and is thus illuminated whenever relay NWE is energized. At such time as the indication relay LKP is picked up and relay PBR is released, a circuit is formed from terminal B over back contact 80 of relay PBR, front contact 84 of relay LKP, back contact 85 of relay NWE, winding 71 of relay RWE and terminal C, and the reverse switch indication relay RWE is energized. With relay RWE picked up, closing its front contact 86, 40 a stick circuit is completed which shunts around the front contact 84 of relay LKP, so that relay RWE is retained energized subsequent to the release of the indication relay LKP. The lamp 70 is connected in multiple with the winding 71 of relay RWE and is illuminated whenever the relay is energized.

To provide the office station with an indication for the occupancy of the detector track section 2T, two relays LK and OS are included in the 45 office station apparatus. The relay LK is controlled over a simple circuit including front contacts 96 and 97 of relays RKP and LKP, respectively. The control of relay OS will be pointed out when the operation of the apparatus is described.

A relay SS and related circuits may also be included in the office station apparatus to provide an optional "stick" operation of the signals. The relay SS and its related circuits will be more fully 50 described hereinafter.

Referring next to the indication line circuit and apparatus for indicating at the office station the occupancy of the track sections in the vicinity of the track switch, this line circuit terminates 55

in two loop circuits at the office station and which loop circuits extend between the line wire 30 and the common return wire CL. One loop circuit comprises an asymmetric unit 104 and the winding of a relay LAP, and the other loop circuit comprises an asymmetric unit 105 and the winding of a relay RAP. The relay LAP controls at its front contact 108 a simple circuit for illuminating a lamp 3L of a track model TM, the circuit being supplied with current from any convenient source the terminals of which are designated BX and CX. The relay RAP controls at its front contact 108 a simple circuit for illuminating the lamp 4L of the track model. The asymmetric units 104 and 105 are disposed reverse to each other, and thus the loop circuit including relay LAP is responsive to current of normal polarity and the loop circuit including relay RAP is responsive to current of reverse polarity. The relays LAP and RAP are slow releasing in character by virtue of the asymmetric units 206 and 207 being connected across the windings of the respective relays.

This indication line circuit is supplied with current at the field station FS over a circuit network controlled by the track relays and the code following relay 2CF. One path of this network includes terminal N of the battery 16, back contact 116 of track relay 1TR, and front contact 118 of track relay 3TR. A second path includes terminal B, front contact 112 of relay 1TR, and back contact 113 of relay 3TR; and a third path involves back contacts 113 and 114 and either back contact of contact member 26 of code following relay 2CF to terminal B of the current source, or front contact of contact member 26 to terminal N of the current source.

It follows that when the track section 1T is occupied and section 3T is unoccupied current of negative or reverse polarity is supplied to this indication line circuit, and the relay RAP at the office station is energized and lamp 4L of the track model TM is illuminated to indicate the occupancy of section 1T. When section 3T is occupied and section 1T is unoccupied, current of positive or normal polarity is supplied to the line circuit and the relay LAP is energized and the lamp 3L is illuminated to indicate the occupancy of section 3T. When both sections 1T and 3T are occupied, then current alternately of normal and reverse polarity is supplied to the line circuit and both relays LAP and RAP are energized to illuminate both lamps 4L and 3L of the track model.

In taking up the operation of the apparatus for controlling the switch and signals from the office station, I shall assume that at the start the switch SW is in its normal position, the signals are all at stop, the track sections are unoccupied and the apparatuses at the stations DS and FS are in the position illustrated, the lamp 68 being illuminated to indicate the normal position of the switch, the lamp 61 being illuminated to indicate the stop position of the signals, and the code transmitter DC being active to operate the code following relays 1CF and 2CF in synchronism. To operate the signal RA to a proceed position for an eastbound train, the operator moves the signal lever LV to its *r* position, closing contacts 31-33, 34-36 and 38-40. During the next period the pilot line circuit is open and the code following relays 1CF and 2CF are released, a control current impulse of positive polarity is applied first to the indication relay RKP at the office station and then to the control relay RGR at the field station over the control and indication line

circuit. To be explicit, current first flows from terminal B of battery 17, over back contact of contact member 25 of relay 1CF, contact 31-33, front contact 92 of relay SS, front contact 93 of relay NWE, wire 53, back contact 54 of relay PBR, 5 asymmetric unit 55, winding 56 of relay RKP and to the terminal C of battery 17, and the relay RKP is picked up. Current then flows over the same circuit up to wire 53, and thence over front contact 94 of relay RKP, terminal 87, line wire 29 10 to the field station FS, terminal 44, front contact 18 of relay 2TR, back contact 19 of relay WR, front contact 48 of relay LMR, winding 49 of relay RGR, asymmetric unit 50 and the common return wire CL to terminal C of battery 17, and 15 the relay RGR is energized. When relay RGR is picked up, closing its front contact 73, the signal control relay RAH is energized as explained hereinbefore and the signal RA is operated to a proceed position. With the picking up of relay 20 RAH, opening back contact 5 interposed in the circuit for relay RMR, the relay RMR is deenergized and released.

During the next period that the pilot line circuit is closed and the code following relays are 25 energized, an indication impulse of current of negative polarity flows from the C terminal of battery 18 at the field station over the common return wire CL to the office station, winding 53 of indication relay LKP, asymmetric unit 57, 30 back contact 54, wire 53, front contact 94, terminal 87, line wire 29, terminal 44, front contact 18, back contact 19, back contact 96 of relay RMR, front contact of the contact member 27 of relay 2CF, and to the N terminal of battery 16, 35 and the indication relay LKP is picked up. The picking up of relay LKP to close its front contact 67 completes the circuit for lamp 63, and lamp 63 is illuminated to indicate the proceed position of the signal RA. It is clear that a control impulse of current from battery 16 is supplied to the relay RKP at the office station and to the relay RGR at the field station during each period the pilot line circuit is open, an indication impulse of current from battery 16 is supplied to the relay LKP during each closed period of the pilot line circuit, and these relays are retained energized from one impulse until the next by virtue of their slow release characteristics. Furthermore, these control impulses and indication impulses are alternately transmitted between the two stations over the same line circuit by virtue of the action of the code following relays. 40 45 50

Starting again with the apparatus in its normal condition, and assuming that the operator desires to operate the signal LA for a westbound train, the lever LV is moved to its *l* position. During the next period that the pilot line circuit is closed and the code following relays are energized, a control impulse of current of negative polarity is supplied first to the relay LKP at the office station and then to the control relay LGR at the field station. The circuit for relay LKP involves the following elements: terminal N of battery 17, front contact of contact member 24 55 of relay 1CF, contact 31-32, front contact 92, front contact 93, wire 53, back contact 54, asymmetric unit 57, winding 58 of relay LKP and terminal C of battery 17. The circuit for relay LGR involves the same elements up to wire 53, 60 and thence over front contact 102 of relay LKP which is now picked up, terminal 87, line wire 29, terminal 44, front contact 18, back contact 19, front contact 45 of relay RMR, winding 46 of relay LGR, asymmetric unit 47 and the common 65 70 75

return wire to terminal C of battery 17. With control relay LGR picked up, closing its front contact 71, the signal control relay LAH is energized and the signal LA is operated to a proceed position in the manner explained hereinbefore. The relay LMR is deenergized and released when the signal control relay LAH is picked up, opening back contact 8. With relay LMR released, an indication impulse of current of positive polarity is returned to the office station during the next period the pilot line circuit is open and the code following relays are released. This impulse of current flows from terminal B of battery 16 over back contact of contact member 28 of relay 2CF, back contact 103 of relay LMR, back contact 79, front contact 78, terminal 44, line wire 29, terminal 87, front contact 102 of relay LKP, wire 53, back contact 54, asymmetric unit 55, winding 58 of relay RKP and the common 20 return wire to the terminal C of battery 16, and the relay RKP at the office station is energized. With relay RKP picked up, closing its front contact 66, the circuit is completed for lamp 62, and that lamp is illuminated to indicate the proceed 25 position of signal LA. From this point on, a control impulse of current of negative polarity from battery 17 is supplied to the control and indication line circuit during each closed period of the pilot line circuit to energize the relays LKP and 30 LGR, and an indication impulse of current of positive polarity from battery 16 is supplied over the control and indication line circuit during each open period of the pilot line circuit to energize the relay RKP, and these relays are retained 35 picked up from one impulse until the next by virtue of their slow release characteristics.

Assuming the signal LA is operated in response to movement of the lever LV to its *l* position and a westbound train enters the track section 3T to shunt the track relay 3TR, an indication impulse is supplied over the indication line circuit to the relay LAP by virtue of the closing of back contact 113 of track relay 3TR, and the lamp 3L of the track model TM is illuminated to indicate 40 the presence of the train in section 3T. When the train advances into section 2T and shunts the track relay 2TR, the release of relay 2TR opens the control and indication line circuit at front contact 78 of relay 2TR, and the exchange 45 of control and indication impulses between the two stations is stopped, and the relays LGR and RKP are deenergized and released. It is to be recalled that the relay LK at the office station is picked up when both relays LKP and RKP are 50 energized, so that when the relay RKP is now released the relay LK is in turn deenergized and releases at the end of its slow release period. During the interval the relay RKP is down and relay LK is picked up current flows from terminal B of battery 17 through winding of relay OS, transfer contact 115 and back contact 116 of relay OS, front contact 117 of relay LK, back contact 118 of relay RKP, controller contact 34—35 of lever LV and terminal C, and relay OS is picked 55 up. Relay OS is retained energized subsequent to the release of relay LK over a stick circuit which includes terminal B, winding of relay OS, transfer contact 115 and front contact 119 of relay OS, wire 128, terminal 87, line wire 29, terminal 44, back contact 121 of track relay 2TR, resistance 122 and common return wire to the terminal C of battery 17. With relay OS thus picked up, closing front contact 123, a simple circuit is completed for a lamp 2L of the track model TM to indicate occupancy of the track section 2T.

When the train enters the track section 1T and shunts the track relay 1TR, the relay RAP is energized in the manner explained hereinbefore, and the lamp 1L is illuminated to indicate the presence of the train in section 1T. 5

To require the operator to first restore the lever LV to its normal *n* position, in order to operate the signal LA for a second and following westbound train, the relay SS would be provided. The relay SS is normally provided with current from terminal B over back contact 125 of relay OS, and contact member 101 of lever LV in its normal position. Relay SS is retained energized subsequent to movement of the lever LV to its *l* position by virtue of a stick circuit that includes two parallel paths, one path of which consists of back contact 126 of relay LK and the other path of which serially includes the front contacts 127 and 128 of relays RKP and LKP, respectively. Thus, during the interval between the release of relay RKP and the release of LK the relay SS is without current and is released, and relay SS upon releasing, opening its front contact 92, opens the circuit network at the office station for the control and indication line circuit. To reclose the control and indication line circuit, the operator must restore lever LV to its normal position and pick up the SS relay, after which he can move the lever LV to its *l* position to cause operation of the signal LA for a second westbound train. If the so-called "stick" operation of the signals is not desired, an emergency switch 129 would be closed and the relay SS constantly retained energized. 25

It is clear that the operation of indicating the occupancy of the track sections when the signal RA is operated for an eastbound train and an eastbound train moves through the sections 1T, 2T and 3T is substantially the same as that described above for a westbound train. 35

Again assuming that the apparatus is in its normal position and the operator desires to operate the track switch SW to its reverse position, the operator depresses the push button PB to pick up the relay PBR and then releases the push button so that relay PBR is released at the end of its slow release period. When the relay PBR is picked up, opening its back contact 89, the normal switch indication relay NWE is deenergized and the lamp 68 is extinguished. During the period that the pilot line circuit is open immediately following the release of relay NWE, a circuit is formed from terminal B of battery 17 at the office station over back contact of contact member 23 of relay 1CF, normally closed contact 9 of push button PB, front contact 130 of relay PBR, wire 53, back contacts 88 and 89 of relays NWE and RWE, terminal 87, line wire 29, terminal 44, front contact 78, back contact 79, front contact 48, winding 49 of relay RGR, asymmetric unit 58, common return wire CL and to terminal C of battery 17, and the relay RGR is picked up by this control impulse of current of positive polarity. During the next period the pilot line circuit is closed, a circuit is formed from the N terminal of battery 17 at the office station, front contact of contact member 23 and over the same circuit traced above up to back contact 78 of relay WR at the field station, and thence over front contact 48, winding 46 of relay LGR, asymmetric unit 47 and the common return wire, and the relay LGR is picked up in response to this control impulse of current of negative polarity. With both relays LGR and RGR energized, the switch controlling relay WR is 75

operated in the manner explained hereinbefore for causing the switch mechanism SM to move the track switch to its reverse position. It should be here noted that the signal control relays are provided with slow-to-pick-up characteristics so that a signal control relay is not selected during the brief interval between the energizing of the first remote control relay and the energizing of the second remote control relay by the switch control impulses. It should also be noted that loop circuits for the relays LGR and RGR are completed during the interval the switch is in mid position over front contact 131 of relay WR and back contact 132 of relay KR.

When the switch is operated to its full reverse position and the relay KR is energized in its reverse position, a reverse switch indication impulse of current of reverse or negative polarity is supplied to the control and indication circuit for energizing the relay LKP at the office station, since the control impulses were stopped and relays LGR and RGR released when relay PBR released. The circuit involves terminal N of battery 16 at the field station, reverse polar contact 133 of relay KR, front contact 134 of relay KR, front contact 131 of relay WR during the slow release period of relay WR, and the following elements: 18, 44, 29, 87, 38, 89, 53, 54, 57, winding 58 of relay LKP and the common return wire. With relay LKP thus energized for the release period of relay WR, closing its front contact 84, the reverse switch indication relay RWE is energized and the lamp 78 is illuminated to indicate the reverse position of the switch.

To move the switch back to its normal position, the operator depresses the push button PB to pick up the relay PBR. When relay PBR is thus picked up, opening its back contact 80, the relay RWE is deenergized and the lamp 78 is extinguished. Immediately following the release of relay RWE, control current impulses alternately of positive and negative polarity are supplied to the control and indication circuit over the contact member 23 of relay 1CF and the front contact 130 of relay PBR, and the control relays RGR and LGR at the field station are energized in the manner explained above. On the next step in the operation, the relay WR is supplied with current of normal polarity, since the circuit network 10 is closed when the switch is moved to its reverse position and the network 11 is open. With relay WR operated to its normal position, the switch is moved back to its normal position.

With relay KR energized by current of normal polarity in response to movement of the switch to the normal position, a normal switch indication impulse is supplied to the control and indication circuit, the circuit connection at the field station being the same as previously described except that it now includes terminal B of the current source and the normal polar contact 135 of relay KR. This indication current impulse being of normal or positive polarity, the relay RKP at the office station is selected. With relay RKP selected and picked up, closing its front contact 81, the normal switch indication relay NWE is energized and the lamp 68 is illuminated.

Assuming that the signal lever LV has been operated to its *r* position, the signal control relay RAH picked up to operate the signal RA and the approach locking relay RMR released in the manner previously described, and that the operator then moves the lever LV back to its normal position *n* with a train approaching the signal RA so that the traffic controlled network 3 is

open, the lamp 61 provides an indication of the completion of the selected time interval interposed by the relay TE in the reenergizing of the locking relay RMR. With relay RAH released, the repeater relay MP is energized, and with relay MP picked up, closing front contact 221, the time element relay TE is operated to close its front contact 217 at the end of its selected operating period and the approach locking relay RMR is reenergized and then held energized over its front contact 222. During the operating period of relay TE, the indication relay LKP is energized by virtue of the indication current impulses supplied over back contact 96 of relay RMR and the lamp 61 remains dark because its circuit is open at back contact 64 of relay LKP. When locking relay RMR is picked up, the relay LKP is deenergized and releases, closing back contact 64 so that the lamp 61 is illuminated. Thus the illumination of the lamp 61 is an indication to the operator of the completion of the time interval interposed in the release of the approach locking.

A similar operation is effected when the lever LV is restored to its *n* position after having been operated to its *l* position to govern the signal control relay LAH and a train has operated the traffic controlled network 6. This time, relay TE, upon operating to close its front contact 218, causes relay LMR to be reenergized. During the operating period of relay TE, the indication relay RKP is energized by current impulses supplied over back contact 103 of relay LMR and the lamp 61 is dark because its circuit is open at back contact 65 of relay RKP. At the completion of the operation of relay TE, the reenergizing of relay LMR causes the lamp 61 to become illuminated and the operator is informed of the restoring of the approach locking relay.

It is to be seen, therefore, that the switch SW and its related signals are operated, and the occupancy of the track section 2T is indicated over the single control and indication line circuit extending between the two stations by virtue of the synchronous operation of the code following relays 1CF and 2CF, the different control conditions and the different indication conditions being effected through the medium of loop circuits selectively responsive to current of positive and negative polarity.

Referring now to Figs. 2a and 2b, the track layout is the same as in Fig. 1b except a track section 4T having a track circuit is formed in the siding track. The apparatus at the field station FS for operating the switch SW and its related signals is substantially the same as in Fig. 1b except two signal repeater relays RP and LP are provided to govern the control and indication line circuit in place of the approach locking relays RMR and LMR. The signal repeater relay RP is energized over a single circuit having two parallel paths, one of which includes a front contact 137 of relay RBH and the other path of which includes a front contact 136 of relay RAH. The relay LP is provided with an energizing circuit having two parallel paths, one path of which includes a front contact 138 of relay LAH and the other path of which includes a front contact 139 of relay LBH. It follows that relay RP is picked up whenever either signal RA or RB is operated to a proceed position, and the relay LP is picked up whenever either signal LA or LB is operated to a proceed position.

The office station apparatus of Fig. 2a includes two slow releasing indication relays LKP and

RKP, a signal control lever LV and signal indication lamps, a switch control push button PB and relay PBR, and switch indication relays NWE and RWE with their respective lamps, the same as in Fig. 1a. The relays LK, OS and SS are omitted but the relay SS and related circuits may be added to the office station apparatus of Fig. 2a if desired.

- The pilot circuit of Figs. 2a and 2b includes
- 10 the line wires PL and CL and the two code following relays 1CF and 2CF, the same as in Figs. 1a and 1b, but the circuit differs from that of Figs. 1a and 1b in that the code transmitter DC is located at the field station and is arranged to
- 15 transmit at times an indication influence from the field station to the office station during the normal open period of the pilot circuit. At the office station, an asymmetric unit 140 is interposed in the circuit adjacent the relay 1CF and placed with its conducting direction toward the winding of relay 1CF so that relay 1CF is energized by current of positive polarity only. A relay OS₁ is associated with the pilot circuit at the office station by having one terminal of its
- 20 25 winding connected with the C battery terminal and the other terminal of its winding connected to the line wire PL through an asymmetric unit 142 and the back contact 143 of relay 1CF, the unit 142 being disposed with its conducting direction toward the winding of relay 1CF so that relay OS₁ is energized by current of negative polarity only. A relay OS₁ is made slow releasing by an asymmetric unit 216 being connected across its winding. At the field
- 30 35 40 station, a connection is provided from terminal N of battery 16 over back contact 144 of track relay 4TR, left-hand or second position contact of contact member 18 of the code transmitter DC and to line wire PL.
- 40 It follows that when the track section 4T is unoccupied the code transmitter DC periodically opens and closes the pilot circuit and the two code relays 1CF and 2CF are operated in synchronism by the impulses of current of positive
- 45 50 55 polarity supplied to the pilot circuit. When the section 4T is occupied and track relay 4TR is released, the code following relays 1CF and 2CF are operated the same as before, and during each half cycle that the contact member 18 swings to the left-hand position an indication impulse of current of negative polarity is supplied to the pilot circuit and relay OS₁ is energized. Relay OS₁, on picking up to close its front contact 145, completes a circuit for lamp 4L of the track model TM₁, and lamp 4L is illuminated to indicate the occupancy of section 4T.
- 60 65 70 It should be pointed out that the code following relay 2CF may be omitted and the contact members 150, 151 and 150 of relay 2CF may be mounted on the code transmitter and operated in step with the contact member 18. In this latter case, the contact members 150 and 151 would be operated by the code transmitter DC to engage right-hand or first position contacts and to engage left-hand or second position contacts in step with the contact members 143, 146 and 148 of relay 1CF for governing the associated control and indication line circuit of Figs. 2a and 2b, and the contact member 150 would be operated by the code transmitter DC in step with the contact member 155 of relay 1CF to govern the associated indication line circuit.

The control and indication circuit of Figs. 2a and 2b includes the line wire 29 and the common return wire CL, the same as in Figs. 1a and 1b,

but the circuit differs from the corresponding circuit of Figs. 1a and 1b in that the circuit of Figs. 2a and 2b provides for control and indication of the track switch and related signals without the use of polarized loop circuits, without the use of asymmetric units to select the relays and without requiring what is commonly known as a split battery arrangement.

It is believed that the control and indication circuit of Figs. 2a and 2b can best be understood by a description of its operation. In describing the operation of the control and indication circuit of Figs. 2a and 2b, I shall assume that the apparatus is in its normal position as illustrated in the drawings and the operator desires to operate the signal RA for an eastbound train. The signal lever LV is moved to its *r* position, closing contacts 31—33 and 98—100. On the next open period of the pilot circuit, when the relays 1CF and 2CF are deenergized, current is supplied first to the office relay RKP and then to the field station relay RGR. The circuit involved extends from terminal B of battery 17 over back contact of contact member 146 of relay 1CF, lever contact 31—33, back contact 147 of relay PBR, front contact 93 of relay NWE, a second back contact 54 of relay PBR, back contact of contact member 148 of relay 1CF, winding 56 of relay RKP and to the terminal C of battery 17. With relay RKP picked up, the connection to the line wire 29 is completed at front contact 94 of relay RKP and current flows over the line wire 29 to the field station and thence through back contact 79 of relay WR, back contact 149 of relay LP, winding 49 of relay RGR, back contact of contact member 150 of code relay 2CF and the common return wire CL to the C terminal of battery 17. With relay RGR picked up, closing its front contact 73, the signal control relay RAH is selected and that relay on picking up operates the signal RA to a proceed position and at the same time energizes the relay RP. With the repeater relay RP picked up, closing its front contact 152, an indication impulse is supplied to the control and indication line circuit during the next period the pilot line is closed. This indication circuit involves terminal B of the battery 16 at the field station, front contact of contact member 151 of relay 2CF, front contact 152 of relay RP, back contact 79, line wire 29, front contact 94 of relay RKP, back contact 54, front contact of contact member 148 of relay 1CF, winding 58 of relay LKP and the common return wire to the C terminal of battery 16. With relay LKP picked up, closing its front contact 67, the lamp circuit for lamp 63 is completed and lamp 63 is illuminated to indicate the proceed position of signal RA.

From this point on, the relay RKP at the office station and the relay RGR at the field station are each supplied with an impulse of current from the battery 17 during each period the pilot circuit is open, and the relay LKP at the office station is supplied with an impulse of current from the battery 16 during each period that the pilot circuit is closed, these control and indication relays being retained energized from one impulse to the next by virtue of their slow release characteristics.

In case the lever LV is moved to its *l* position to close contacts 31—32 and 97—99, the signal LA is operated to a proceed position and this position is indicated by the illumination of the lamp 62. This time, current flows from ter-

5 minal B of battery 17 over front contact of contact member 146 of relay 1CF, contact 31-32, back contact 147, front contact 93, back contact 54, front contact of contact member 148 of relay 5 1CF, winding 56 of relay LKP and to the terminal C, and the relay LKP on being energized completes the circuit to the line wire 29, and current then flows over the same circuit thus traced up to front contact 93 and thence over 10 front contact 102 of relay LKP, line wire 29 to the field station, back contact 79, back contact 154 of relay RP, winding 46 of relay LGR, front contact of contact member 150 of relay 2CF, and the common return wire to the C terminal of battery 17. The picking up of relay LGR, closing its front contact 77, completes the circuit for the signal control relay LAH, and that relay is picked up to operate the signal LA and also to energize the relay LP.

20 An indication impulse is now supplied from battery 16 for energizing the relay RKP during the next period the pilot line circuit is open, the circuit extending from terminal B of battery 16 over back contact of contact member 151 of relay 2CF, front contact 153 of relay LP, back contact 79, line wire 29, front contact 102, back contact 54, back contact of contact member 148 of relay 1CF, winding 56 of relay RKP and the common return wire to the C terminal of battery 16. With relay RKP picked up, closing its front contact 66, the circuit for lamp 62 is completed and the lamp is illuminated to indicate the proceed position of signal LA. From this point on, the relays LKP and LGR are supplied 30 with a current impulse from battery 17 during each period the pilot circuit is closed, and the relay RKP is supplied with an impulse of current from the battery 16 during each period the pilot circuit is open.

40 Assuming the apparatus of Figs. 2a and 2b to be at its normal position and that the switch SW is to be operated to its reverse position, the operator would depress the push button PB for an interval to energize the relay PBR, in the manner previously explained. With relay PBR picked up, the normal switch indication relay NWE and lamp 68 are deenergized, as previously explained. Current now flows over the control and indication circuit to energize the relays LGR 45 and RGR, the circuit involving terminal B of battery 17, contact 9 of push button PB, front contact 130 of relay PBR, back contacts 89 and 88, line wire 29, back contact 79, and thence over back contact 154 of relay RP and winding 46 of relay LGR to the common return wire when the contact member 150 engages its front contact, and over the back contact 149 of relay LP and the winding 49 of relay RGR to the common return wire when contact member 150 engages its back contact. With both control relays LGR and RGR energized, the switch controlling relay WR is supplied with current of reverse polarity, in the manner previously explained, to bring about the movement of the track switch to its reverse position. When the switch is moved to its full reverse position and relay KR is operated to its reverse position a reverse switch indication impulse is returned to the office station, the circuit involving terminal B of battery 16, front contact of contact member 151 of relay 2CF, reverse polar contact 133 of relay KR, front contact 134, front contact 131 of relay WR, line wire 29, back contacts 89 and 88, back contact 54, front contact of contact member 148 of relay 75 1CF, winding of relay LKP, common return wire

CL and to terminal C of battery 16. With relay LKP picked up, closing its front contact 84, the reverse switch indication relay RWE and lamp 78 are energized in the manner previously explained.

To move the track switch back to its normal position, the operator would depress the push button PB to pick up the relay PBR for an interval. During the interval relay PBR is picked up, control current is supplied over the front contact 130 of relay PBR to the control and indication line circuit for energizing the relays LGR and RGR simultaneously, the two relays LGR and RGR being energized over the contact member 150. This time, when the relays LGR and RGR are both picked up, the switch controlling relay WR is energized with current of normal polarity, since the network 10 is closed and the network 11 is open, and the switch is operated back to its normal position. When the switch is moved to its full normal position and the relay KR is energized in its normal position, a normal switch indication impulse is returned to the office station over the control and indication line circuit, the circuit being the same as described for the return of a reverse switch indication impulse, except at the field station it is completed at the back contact of contact member 151 and includes the normal polar contact 135 of relay KR, and at the office station the circuit is completed to the relay RKP over the back contact of contact member 143 of relay 1CF. With relay RKP thus energized, closing its front contact 81, the normal switch indication relay NWE and lamp 68 are energized to indicate the normal 30 position of the switch.

It is to be seen, therefore, that, with the apparatus constructed as shown in Figs. 2a and 2b, control and indication impulses are exchanged between the two stations over a single line circuit 40 by virtue of a synchronous operation of the code transmitter DC and the code following relays of the pilot circuit. The operation of the control and indication circuit of Figs. 2a and 2b differs from that of Figs. 1a and 1b in that the currents 45 in the line circuit for control and indication flow in opposite directions in Figs. 2a and 2b, whereas the currents flow in the same direction in Figs. 1a and 1b. Also in Figs. 2a and 2b, the control relays LGR and RGR at the field station and the 50 indication relays LKP and RKP at the office station are selected by the definite time relation at which the relays are connected with the line circuit by the code transmitter and the code following relays in place of the polarity relation of the 55 current supplied to the line circuit as used in Figs. 1a and 1b.

In Figs. 2a and 2b, the indication circuit including line wire 30 for indicating the presence of a train in the track sections is governed by 60 contact members of the code following relays of the pilot circuit in such a manner as to indicate occupancy of each of the track sections 1T, 2T and 3T in any arrangement, and also to provide a special indication which may be used when 65 indication of a track section is not required. At the office station this indication circuit is provided with four parallel loop circuits between the line wire 30 and the common return wire CL, two of which loop circuits are completed over a 70 front or first position contact of contact member 155 of code relay 1CF and the other two of which loop circuits are completed over the back or second position contact of contact member 155. To be explicit, the first loop circuit includes an 75

- asymmetric unit 156 and the winding of a relay 1S; the second loop circuit includes an asymmetric unit 157 and the winding of a relay 2S; the third loop circuit includes an asymmetric unit 158 and the winding of a relay 3S; and the fourth circuit includes an asymmetric unit 159 and the winding of a relay 4S. The units 156 and 157 of the first and second loop circuits are disposed reverse to each other, and the units 158 and 159 of the third and fourth loop circuits are disposed reverse to each other, and each of the four relays 1S, 2S, 3S and 4S is made slow to release by virtue of an asymmetric unit connected across the winding of the relay, as will be understood by an inspection of Fig. 2a. It is clear that current of positive polarity supplied to the line wire 30 when the code relay 1CF is energized selects the relay 1S and current of negative polarity supplied to the line wire 30 at such time selects the relay 2S.
- 20 In like fashion, current of positive polarity supplied to the line wire 30 when the code relay 1CF is released selects relay 3S, and current of negative polarity selects the relay 4S.
- 25 The relays 1S, 2S, 3S and 4S control a circuit network for illuminating the lamps 1L, 2L and 3L of the track model TM1, and a fourth lamp XL. Lamps 1L, 2L and 3L of the track model correspond to the sections 1T, 2T and 3T, respectively, and the lamp XL corresponds to the condition of a special relay XR at the field station.
- 30 At the field station, the indication circuit is provided with impulses of current positive and negative in polarity in step with the operation of the contact member 160 of the code relay 2CF in accordance with the arrangement of a circuit network which is controlled by the track relays 1TR, 2TR and 3TR and the special relay XR. The track relays are responsive to traffic conditions on their respective track sections, and the relay XR would be used to check the condition of certain parts of the apparatus at the field station. For example, the relay XR could be used to check the voltage of the battery 16. This circuit network and the code member 160 are capable of establishing for each combination in which the track sections can be occupied a distinctive polarity pattern for the current impulses supplied to the indication circuit, and a different pattern for the release condition of the relay XR, with the result that the relays of the loop circuits at the office station are selected in corresponding combinations and the lamps of the track model are illuminated in combinations corresponding to the combinations in which the track sections are occupied, and the lamp XL is illuminated according to the condition of the XR relay.
- 35 In explaining the operation of the indication circuit of Figs. 2a and 2b, I shall first describe in step-by-step fashion the operation which takes place when an east-bound train travels through the track sections 1T, 2T and 3T. When the train enters track section 1T and shunts track relay 1TR, the indication circuit is supplied with current impulses which, starting from the instant the pilot circuit is closed and the code relays are energized, have a polarity pattern alternately negative and positive. During the period 40 the code relays are energized, the circuit extends from terminal N of battery 16 over back contact 163 of relay 1TR, front contact 164 of relay 3TR, front contact of code contact member 160 of relay 2CF, line wire 30, front contact of contact member 155 of code relay 1CF, asy-

metric unit 157, winding of relay 2S and the common return wire to terminal C of battery 16, and relay 2S is energized. During the period the pilot circuit is open and the code relays are de-energized, the circuit extends from terminal B 45 of battery 16 over front contact 161 of relay 2TR, back contact 162 of relay 1TR, back contact of contact member 160 of relay 2CF, wire 30, back contact of contact member 155 of relay 1CF, asymmetric unit 158, winding of relay 3S and 10 the common return wire to the terminal C of battery 16, and relay 3S is energized. With both relays 2S and 3S picked up, the lamp 1L is illuminated over a circuit having two branch paths, one path of which includes front contact 165 of 15 relay 2S and the other path of which includes front contact 166 of relay 3S and back contact 167 of relay 1S.

When the train advances and enters section 2T and occupies both sections 1T and 2T so that 20 both track relays 1TR and 2TR are shunted but track relay 3TR is picked up, the polarity pattern of the indication current is that of successive impulses of current of negative polarity. When the pilot circuit is closed, a first circuit is completed from terminal N of battery 16 over back contact 163 of relay 1TR, front contact 164 of relay 3TR, front contact of contact member 160, wire 30, front contact of contact member 155, unit 151, winding of relay 2S and the common return wire 30 to terminal C of battery 16, and relay 2S is selected. A second circuit involves terminal N of battery 16, back contact 168 of relay 2TR, front contact 169 of relay 3TR, back contact of contact member 160, wire 30, back contact of contact member 155, unit 159, winding of relay 4S and the common return wire to terminal C of battery 16, and relay 4S is selected. With relays 2S and 4S picked up, the lamp 1L is illuminated over front contact 165 of relay 2S, and the lamp 2L is illuminated over front contact 170 of relay 4S.

Let us say that the train is long enough to occupy all three sections 1T, 2T and 3T so that all three track relays 1TR, 2TR and 3TR are shunted. 45 The polarity pattern of the indication current is that of an impulse of current of negative polarity during the period the pilot circuit is closed and no impulse of current during the period the pilot circuit is open. When the pilot circuit is closed, a circuit now extends from terminal N of battery 16 over back contact 171 of relay 2TR, back contact 172 of relay 1TR, back contact 173 of relay 3TR, front contact of contact member 160, wire 30, front contact of contact member 155, unit 151, winding of relay 2S and the common wire to terminal C of battery 16, and the relay 2S is energized. During the period the pilot circuit is open, no circuit is completed and no impulse of current is supplied to the indication circuit. With relay 2S picked up, the lamp 1L is illuminated over front contact 165 of relay 2S; the lamp 2L is illuminated over front contact 174 of relay 2S and back contact 175 of relay 3S; and the lamp 3L is illuminated over back contacts 176 and 177 of relays 4S and 3S, respectively, and front contact 178 of relay 2S.

As the train advances, the section 1T is vacated so that relay 1TR is picked up and relays 2TR and 3TR remain shunted. Under this combination of relays, the polarity pattern of the current supplied to the indication circuit is, starting with the pilot circuit closed, that of impulses of current alternately positive and negative in polarity. The first circuit consists of terminal 70 75

B of battery 16, front contact 179 of relay 1TR, back contact 173 of relay 3TR, front contact of contact member 160, wire 30, front contact of contact member 155, unit 156, winding of relay 1S and the common return wire to terminal C of battery 16, and relay 1S is selected. The other circuit now completed extends from terminal N of battery 16 over back contact 168 of relay 2TR, front contact 180 of relay 1TR, back contact of contact member 160, wire 30, back contact of contact member 155, unit 159, winding of relay 4S and the common return wire to terminal C, and relay 4S is energized. With relays 1S and 4S selected, the lamp 2L is illuminated over front contact 170 of relay 4S, and the lamp 3L is illuminated over front contact 181 of relay 4S and front contact 182 of relay 1S.

As the train advances, the section 2T is next vacated and the relay 2TR is energized so that 20 relays 1TR and 2TR are now picked up and the relay 3TR is shunted. Under this combination of the relays, the indication current has a polarity pattern of successive impulses of current of positive polarity. The first circuit consists of battery terminal B, front contact 179 of relay 1TR, back contact 173 of relay 3TR, front contact of contact member 160, wire 30, front contact of contact member 155, unit 156, winding of relay 1S, common return wire and terminal C, and relay 1S is energized. The other circuit extends from terminal B over front contact 161 of relay 2TR, back contact 183 of relay 3TR, back contact of contact member 160, wire 30, back contact of contact member 155, unit 158, winding of relay 3S, common return wire and terminal C, and relay 3S is energized. The lamp 3L is now illuminated over front contact 184 of relay 3S and back contact 185 of relay 2S. When the train moves east and vacates section 3T so that all 40 three track relays are picked up, the indication circuit is without current and the lamps of the track model TMI are dark.

In the event one train occupies section 1T, a second train occupies section 3T and the section 45 2T is unoccupied, the relays 1TR and 3TR are shunted and relay 2TR is picked up. Under this combination of the relays, the polarity pattern of the indication current is that during the closed period of the pilot circuit no impulse of current is supplied to the indication circuit and during the open period of the pilot circuit an impulse of current of positive polarity is supplied to the indication circuit. This time, the circuit consists of terminal B, front contact 161 of relay 2TR, back contact 183 of relay 3TR, back contact of member 160, wire 30, back contact of member 155, unit 158, winding of relay 3S, common return wire and terminal C, and relay 3S is energized. The lamp 1L is now illuminated over front contact 166 of relay 3S and back contact 167 of relay 1S, and the lamp 3L is illuminated over front contact 184 of relay 3S and back contact 185 of relay 2S.

Again assume the track section 2T is occupied and sections 1T and 3T are unoccupied so that track relay 2TR is shunted and track relays 1TR and 3TR are picked up. The polarity pattern of the indication current is now that no impulse is supplied during the closed period of the pilot circuit and current of negative polarity is supplied during the open period of the pilot circuit. The indication circuit now consists of terminal N, back contact 168 of relay 2TR, front contact 169 of relay 3TR, back contact of member 160, wire 30, back contact of member 155, unit 159,

winding of relay 4S, common return wire and terminal C, and relay 4S is selected. The lamp 2L is now illuminated over front contact 170 of relay 4S.

When the track sections are unoccupied and relay XR is deenergized due to some condition of the apparatus, the indication circuit is supplied with an impulse of current of positive polarity during the closed period of the pilot circuit and is without current during the period the pilot circuit is open. The circuit is completed from terminal B over back contact 186 of relay XR, and thence as previously traced, and the relay 1S is selected. With relay 1S picked up, the lamp XL is illuminated over front contact 187 of relay 1S, back contact 188 of relay 4S and back contact 189 of relay 3S.

It follows from the foregoing description of the indication circuit and apparatus of Figs. 2a and 2b that three continuing indications, which are independent of each other and may, therefore, be arranged in any combination, are transmitted over a single two-wire line circuit, and a fourth indication is transmitted when none of the other three indications are being used.

In Fig. 3, the track layout and signals are the same as in Fig. 1b, except that an approach track section A1T having a track circuit is formed to the left of section 1T. The signals and track switch of Fig. 3 are governed by apparatus at the field station which is controlled from the office station over a control and indication circuit substantially the same as that of Figs. 2a and 2b, and a description of this much of the apparatus need not be repeated, certain of the relays and circuits not being shown in Fig. 3 for the sake of simplicity.

In the form of the invention disclosed in Fig. 3, the pilot circuit extending between the two stations is operated by a code transmitter DC1 at the office station, and which transmitter is normally inactive and is approach controlled by traffic conditions over the associated indication line circuit and by circuits governed by the signal lever LV and the switch controlling push button PB. At the field station FS, a code repeater relay 2CFP and another relay PR are associated with the pilot circuit in a manner to be shortly described.

The code transmitter DC1 may be of the same form as in Fig. 1a, but as shown in Fig. 3 it comprises two slow acting relays T and TA.

At such time as positive energy is applied to the wire 206, in a manner to later appear, current flows over back contact 201 of relay TA, winding of relay T and to the terminal C of the current source, and relay T is picked up. Relay T, on picking up, closing front contact 202, completes a circuit and current flows from wire 200 over front contact 201, winding of relay TA and terminal C, and the relay TA is picked up. With relay TA picked up, the circuit for relay T is opened at back contact 201, and relay T releases at the end of its slow release period. Relay T, upon releasing to open front contact 202, removes current from relay TA, and relay TA is released at the end of its slow release period. With both relays TA and T released and restored to their normal positions, the operating cycle explained above is repeated, and is periodically repeated as long as positive energy is applied to the wire 200. The parts are so proportioned that the operating cycle of the code transmitter DC1 requires one-half second, or, in other words, its code frequency is 120 cycles per minute, since 75

I have assumed for illustrating my invention a code frequency of 120 cycles per minute for the pilot line circuit.

- 5 The pilot line circuit of Fig. 3 is controlled at back contact 293 of relay T, and consequently when the code transmitter DC1 is active the code following relays 1CF and 2CF are operated sequentially, the same as described for the other forms of the invention.
- 10 10 The code repeater relay 2CFP is energized over two branch paths, one of which includes front contact of contact member 190 of code relay 2CF, and the other path of which includes front contact 191 of relay PR. The repeater relay 2CFP is provided with slow pick-up and slow release characteristics, the parts being so adjusted that the pick-up period and the release period of relay 2CFP are each substantially equal to one-fourth of the operating cycle of the code 15 following relays of the pilot circuit. Hence, when relay 2CFP is operated by virtue of the circuit completed at front contact of contact member 190 of relay 2CF, the two relays 2CF and 2CFP are operative to divide each code cycle into substantially four equal periods, which periods are about one-eighth second each in duration, when the code frequency of the pilot circuit is 120 cycles per minute and each code cycle is of a duration of substantially one-half second. 20 Starting from the instant the pilot circuit is closed, the relay 2CF is picked up and relay 2CFP is released during the first one-eighth second period of the cycle so that during this first one-eighth second period the front contacts of the 25 contact members 160, 190 and 193 of relay 2CF and the back contacts of contact members 194 and 198 of relay 2CFP are closed; during the second one-eighth second period of the cycle the pilot circuit is still closed and both relays 2CF and 2CFP are picked up so that the front contacts of the contact members of both relays are closed; during the third one-eighth second period the pilot circuit is opened and relay 2CF immediately releases but relay 2CFP remains 30 picked up due to its slow release feature so that the back contacts of the contact members of relay 2CF and the front contacts of the contact members of relay 2CFP are closed during the third one-eighth second period; and during the 35 fourth one-eighth second period the pilot circuit is still open and both relays 2CF and 2CFP are released so that the back contacts of the contact members of both relays are closed. This operation of relays 2CF and 2CFP is repeated for each 40 successive code cycle. It should be noted, however, that the code relay 2CF of Fig. 3 operates sequentially with the relay 1CF; the same as in the previous cases. The relay PR is introduced in 45 the field station apparatus to at times effect approach control of the code transmitter TC1, in a manner to shortly appear.
- 50 In Fig. 3, the indication line circuit for indicating the occupancy of the track sections, and which circuit includes line wire 38, is provided at 55 the office station with four parallel loop circuits similar to Fig. 2a, and the description thereof need not be repeated except to point out that these loop circuits are controlled over the contact member 155 of code relay 1CF.
- 60 65 The track model TM2 of Fig. 3 is similar to the track model TM of Fig. 1a except a lamp A1L has been added for indicating the occupancy of section A1T. The lamps of the track model 70 75 TM2 are controlled by the office station indica-

tion relays over simple circuits which will be readily understood by an inspection of Fig. 3.

In describing the operations of the indication circuit of Fig. 3 for indicating the occupancy of the track sections and for approach controlling the code transmitter, I shall consider the operation effected in response to an eastbound train passing through the four successive track sections, the eastbound signal RA being operated after the train enters section A1T. It is noted 10 that normally the code transmitter DC1 is inactive, the code relays 1CF and 2CF are de-energized so that their respective contact members are in engagement with back or second position contacts, and the lamps of the track model TM2 are dark. When the train enters the approach section A1T and shunts the track relay A1TR, the relay PR is energized by virtue of a circuit completed from terminal B of battery 16, over back contact 192 of relay A1TR, 20 front contact of contact member 193 of relay 2CF, winding of relay PR and terminal C, and the relay PR is picked up at the end of its slow pick-up period. Relay PR on picking up, closing its front contact 191, causes current to be supplied to 25 relay 2CFP, and relay 2CFP, on picking up, completes an indication circuit for energizing the relay 3S at the office station. This indication circuit can be traced from terminal B of battery 16 over back contact 192 of relay A1TR, front contact of 30 contact member 194 of relay 2CFP, back contact of contact member 160 of relay 2CF, line wire 38, back contact of contact member 155 of relay 1CF, asymmetric unit 158, winding of relay 3S and the common return wire to terminal C of 35 battery 16. The relay 3S is now picked up, closing its front contacts 195 and 196, the closing of front contact 195 being effective to supply positive energy to wire 200 for operating the code transmitter DC1 in the manner explained here- 40 inbefore, and the closing of front contact 196 completing the circuit for lamp A1L for illuminating the lamp A1L to indicate the presence of the train in the section A1T. Operation of the code transmitter DC1 and in turn of the code 45 following relay 2CF causes the relay PR to be deenergized and released, since the slow pick-up period of relay PR is made greater than the interval the back contact of contact member 193 of relay 2CF is closed. That is to say, the pick- 50 up period of relay PR is greater than one-half the code cycle of the pilot circuit. With relay PR released, the relay 2CFP is supplied with current over front contact of contact member 190 of relay 2CF and is operated with the relay 55 2CF to divide the code cycle into four periods, as already explained. The previously traced indication circuit for energizing relay 3S in response to the train in section A1T is now formed during the third one-eighth second period of 60 each code cycle, the connection being completed at back contact 192 of relay A1TR, front contact of contact member 194 of relay 2CFP and back contact of contact member 160 of relay 2CF, and thus the relay 3S at the office station is retained 65 picked up, with the result the code transmitter DC1 is continuously operated and the lamp A1L is continuously illuminated.

The track relay 1TR is shunted when the head end of the train enters the section 1T, so that 70 both track relays 1TR and A1TR are now released. The indication relay 3S continues to be supplied with current of positive polarity during the third one-eighth second period of each code cycle, so that the lamp A1L is illuminated and 75

the code transmitter is operated the same as when the train occupied the section A!T only. During the second one-eighth second period of each code cycle, an impulse of current of negative polarity is supplied to the indication circuit for energizing the relay 2S, the connection at the field station being completed from battery terminal N over back contact 197 of track relay 1TR, front contact of contact member 198, and front contact of contact member 160 of relay 2CF, and the connection being completed at the office station over the front contact of contact member 155 of relay 1CF, unit 157 and winding of relay 2S. With relay 2S picked up, closing front contact 199, the lamp 1L is illuminated to indicate the occupancy of section 1T. It should be noted that in case the train is short so that its rear end vacates the section A!T and the train occupies section 1T only, the relay A!TR picks up and deenergizes the indication relay 3S to discontinue the display of the lamp A!L, and the code transmitter DC1 is controlled over front contact 204 of relay 2S.

Assuming the train is of such length that when its front end enters the section 2T the train extends over sections A!T, 1T and 2T, the indication relays 2S and 3S are retained energized by indication impulses supplied during the second and third one-eighth second period of each code cycle, as explained above, so that the lamps A!L and 1L are still illuminated. With the track relay 2TR shunted, impulses of current of positive polarity are supplied to the indication circuits during the first one-eighth second period of each code cycle to energize relay 1S at the office station, the connection being completed at back contact 205 of relay 2TR, back contact of member 198 of relay 2CFP and front contact of member 160 of relay 2CF. The lamp 2L is now illuminated over front contact 215 of relay 1S to indicate the occupancy of section 2T. It should be noted that with a short train which might occupy section 2T only, the operation of the code transmitter is maintained by the circuit including front contact 210 of relay 1S.

Assuming the train is of such length that when its head end enters section 3T the train occupies all four of the track sections, the relays 1S, 2S and 3S are retained energized by indication impulses supplied during the first, second and third one-eighth second period of each code cycle, and the lamps A!L, 1L and 2L are still illuminated. The indication relay 4S is now energized by impulses of current of negative polarity supplied during the fourth one-eighth second period of each code cycle, the connection being completed at back contact 214 of relay 3TR, back contact of member 194 of relay 2CFP and back contact of member 160 of relay 2CF. The closing of front contact 206 of relay 4S completes the circuit for lamp 3L, and lamp 3L is illuminated to indicate the presence of the train in section 3T, and the closing of front contact 209 of relay 4S completes another parallel path for supplying energy to the code transmitter DC1.

Starting again with the apparatus in its normal condition and assuming a westbound train enters the section 3T and shunts track relay 3TR, the indication relay 4S is picked up by virtue of current supplied from terminal N over back contact 207 of relay 3TR, and back contacts of members 194, 160 and 155 of relays 2CFP, 2CF and 1CF, respectively. With relay 4S picked up, closing its front contacts 208 and 209, the lamp 3L is illuminated and positive energy is supplied to the

code transmitter DC1 to start operation of the transmitter. The operations effected from this point on in response to the westbound train occupying the sections 2T, 1T and A!T are similar to the operations effected in response to the eastbound train occupying these sections, and it is thought the description need not be repeated.

Starting again with the apparatus in the normal condition and assuming a signal is to be operated while the track sections are unoccupied, the operator moves the signal lever LV of Fig. 3 to either its *l* or *r* position to control the relays LGR and RGR in the manner explained in Figs. 2a and 2b. When the signal lever LV is moved to either position *l* or *r*, positive energy is supplied to wire 200 over the contact member 211 of lever LV, and the code transmitter DC1 is operated to operate the code following relays so that the signal control for operating the signals and the indication of the positions of the signal is effected over the control and indication line circuit in the same manner as described for Figs. 2a and 2b.

Again, if the operator desires to move the track switch, and to that end depresses the push button PB to pick up the relay PBR, positive energy is applied to wire 200 over a connection including back contacts 212 and 213 of the switch indication relays NWE and RWE so that the code transmitter DC1 is set into operation and the relays LGR and RGR are made responsive to the switch controlling impulse and the position of the switch is indicated over the control and indication line circuit in the same manner as described for Figs. 2a and 2b.

It is apparent that with the apparatus of Fig. 3, the code transmitter is made active only when a signal or the track switch is to be operated and the occupancy of a track section is to be indicated, and that the indications of the occupancy of four track sections are transmitted over a single two-wire line circuit.

Although I have herein shown and described only three forms of apparatus embodying my invention, it is understood that various changes and modifications may be made therein within the scope of the appended claims without departing from the spirit and scope of my invention.

Having thus described my invention, what I claim is:

1. In a remote control system, an office station and a field station, a pilot circuit connecting said stations and including in series the windings of two code following relays one at each station, a code transmitter operative to periodically open and close said circuit to operate said relays in synchronism, and a control and indication line circuit extending between said stations jointly controlled by said relays and made effective to alternately exchange current impulses between said stations by such synchronous operation of said relays.

2. In a remote control system, an office station and a field station, a pilot circuit connecting said stations and serially including the windings of two code following relays, said relays located one at each of said stations, a code transmitter operative to code said circuit to operate said relays in synchronism, and a control and indication circuit extending between said stations jointly controlled by said relays and made effective to alternately exchange current impulses between said stations according to the code operation of said transmitter by such synchronous operation of said relays.

3. In a remote control system, an office station and a field station, a pilot circuit extending between said station and serially including the windings of two code following relays, said relays located one at each of said stations, a code transmitter operative to periodically open and close said circuit to operate said relays in synchronism, a line circuit extending between said stations, control apparatus at the field station having a plurality of different conditions, controlling means at the office station having a position for each condition of the control apparatus, and means governed by said relays to selectively connect said controlling means and control apparatus to said line circuit to establish the condition of the control apparatus corresponding to the position of the controlling means.
4. In a remote control system, an office station and a field station, a control device at the field station, an indication device at the office station, a pilot circuit extending between said stations and including in series the windings of two code following relays one at each station, a code transmitter operative to periodically open and close said circuit for operating said relays in synchronism, a line circuit extending between said stations, a current source, means governed by said relays to connect the current source with said line circuit first at the office station and then at the field station and to periodically alternate the connections, and other means governed by said relays to alternately connect the control and indication devices with said line circuit to energize the devices each with current supplied to said line circuit at the other station.
5. In a remote control system, a mechanism having different positions, a field station at said mechanism having a control means selectively responsive to current of normal and reverse polarities for operating said mechanism, an office station having an indication means selectively responsive to current of normal and reverse polarities for indicating the positions of said mechanism, a pilot circuit extending between said stations and including in series the windings of two code following relays one at each station, a code transmitter operative to periodically open and close said circuit to operate said relays in synchronism, another circuit extending between said stations and connected to said control and indication means, a control lever at the office stations, means controlled by said lever and the office station code relay to supply current impulses of either normal or reverse polarity to said other circuit during the opened or closed periods of the pilot circuit respectively to selectively energize said control means for operating the mechanism, and means controlled by said mechanism and the field station code relay to supply current impulses of either normal or reverse polarity to said other circuit during the opened or closed periods of the pilot circuit respectively to selectively energize said indication means, and said code following relays arranged that current can be supplied to said other circuit at but one station at a time.
6. In a remote control system, an office station and a field station, a pilot circuit extending between said stations and including two relays one at each station, said relays each operable to a first position when energized and to a second position when deenergized, coding means operative to periodically open and close said circuit to operate the relays in synchronism, a control circuit extending between said stations, two loop circuits at each station connected with said control circuit, said loop circuits each including a control unit and each operative to pass current in one direction only and the two loop circuits at each station arranged for opposite directions, a control lever at the office station having a first and a second position, means including the first position of the lever and the first position of the office relay to supply current of reverse polarity to said control circuit to energize the unit of a particular one of the field station loop circuits, means including the second position of the lever and the second position of the office relay to supply current of normal polarity to said control circuit to energize the unit of the other field station loop circuit, means controlled by the unit of said one field station loop circuit and the second position of the field station relay to supply current of normal polarity to the control circuit to energize the unit of a particular one of the office station loop circuits and means controlled by the unit of said other field station loop circuit and the first position of the field station relay to supply current of reverse polarity to the control circuit to energize the unit of the other office station loop circuit.
7. In a remote control system, a railway track provided with a signal for governing traffic over said track, a field station located at said signal and having a control device for governing said signal, an office station remote from the signal and having an indication device for indicating the position of said signal, a pilot circuit extending between said stations and including two code following relays one at each station, a code transmitter operative to periodically open and close said circuit for operating said relays in synchronism, another circuit extending between said stations, a current source, means controlled by said relays to periodically and alternately connect said control and indication devices to said other circuit, and other means governed in part by said relays to periodically connect the current source to said other circuit alternately at the two stations to energize said control and indication devices each by current supplied to said other circuit at the opposite station whereby the signal is continuously controlled from the office station and the indication device is continuously controlled from the field station.
8. In a remote control system, a stretch of railway track, a right signalling means and a left signalling means to govern traffic through the stretch, a field station adjacent said stretch, a remote office station, a pilot circuit extending between said stations including two code following relays one at each station, said code relays each operable to a first and a second position, coding means to periodically open and close said circuit to operate said relays to their first and second positions in synchronism, another circuit extending between said stations, a first and a second loop circuit at each station connected to said other circuit, each of said loop circuits including a control unit and operative to pass current of one polarity only and the two circuits at each station arranged for opposite polarities, a signal lever at the office station having a right and a left position, means including the right position of the lever and the second position of the office relay to supply current of normal polarity to said other circuit to energize the unit of the first field loop circuit, means including the left position of the lever and the first position of the office relay to supply current of

reverse polarity to said other circuit to energize the unit of the second field loop circuit, circuits governed by the control units of the field loop circuits for selectively operating said right and left signalling means, means governed by said right signalling means and the first position of the field relay to supply current of reverse polarity to said other circuit to energize the unit of the first office loop circuit, means governed by said left signalling means and the second position of the field relay to supply current of normal polarity to said other circuit to energize the unit of the second office loop circuit, and indicating devices selectively governed by the control units of the office loop circuits.

9. In a remote control system, an office station and a field station, a pilot circuit extending between said stations and including in series the windings of two code following relays one at each station, said relays each operable to a first and a second position, coding means having an operation cycle of a predetermined period and operative to periodically open and close said pilot circuit for substantially one-half of each cycle respectively to operate said relays to their first and second positions in synchronism, a slow release control relay at the field station and a slow release indication relay at the office station, said slow release relays having slow release periods greater than one-half the period of said operation cycle, a line circuit extending between said stations, a current source at each station, means including the first position of each of said code relays to connect said control relay at the field station and the current source at the office with the line circuit to continuously energize the control relay due to its slow release period bridging the second position periods of the code relays, and means including the second position of each of said code relays to connect said indication relay at the office station and the current source at the field station to the line circuit to continuously energize the indication relay due to its slow release period bridging the first position periods of the code relays.

10. In a remote control system, an office station and a field station, a pilot circuit extending between said stations and serially including the windings of two code following relays one at each station, said relays each operable to a first and a second position, coding means having an operation cycle of a predetermined period and operative to periodically open and close said circuit to operate said relays to their first and second positions in synchronism with each relay at its respective positions for substantially one-half of each cycle, a control unit and a signalling means at the field station, an indication unit and a lamp at the office station, said control and indication units provided each with a slow acting period greater than one-half the period of said operation cycle, a control lever, a line circuit extending between said stations, a current source at each station, means governed by said lever and including the first position of each of said code relays to connect the control unit at the field and the current source at the office with said line circuit to continuously energize the control unit for governing said signalling means, and means governed by the signalling means and including the second position of each of said code relays to connect the indication unit at the office and the current source at the field to said line circuit to continuously energize the indication unit for illuminating the lamp.

11. In a remote control system, an office station and a field station, a pilot circuit extending between said stations and serially including the windings of two code following relays one at each station, said relays each operable to a first and a second position, coding means having an operation cycle of a predetermined period and operative to periodically open and close said circuit to operate said relays to their first and second positions in synchronism with each relay at its respective positions for substantially one-half of each cycle, a first and a second slow release control relay and a signalling means at the field station, a first and a second slow release indication relay and a pair of lamps at the office station, said control relays and said indication relays provided each with a slow release period greater than one-half of said operation cycle, a control lever having a first and a second position, a line circuit extending between said stations, a current source at each station, means including the first position of the lever and the first position of both code relays to connect the current source at the office and the first control relay with said line circuit for continuously energizing that relay because of its slow release period to establish a first condition of said signalling means, means including the second position of the lever and the second position of both code relays to connect the current source at the office and said second control relay with said line circuit for continuously energizing that relay because of its slow release period to establish a second condition of the signalling means, means including the first condition of the signalling means and the second position of both code relays to connect the current source at the field and said first indication relay with said line circuit for continuously energizing that relay because of its slow release period to illuminate a first one of said lamps, and means including the second condition of the signalling means and the first position of both code relays to connect the current source at the field and said second indication relay with said line circuit for continuously energizing that relay because of its slow release period to illuminate the second one of said lamps.

12. In a remote control system, an office station and a field station, a pilot circuit extending between said stations and serially including the windings of two code following relays one at each station, said relays each operable to a first and a second position, coding means having an operation cycle of a predetermined period and operative to periodically open and close said circuit to operate said relays to their first and second positions in synchronism with each relay at its respective positions for substantially one-half of each cycle, a slow release control relay and a signalling means at the field station, a slow release indication relay and an indicator as well as a control lever at the office station, said control and indication relays provided each with a slow release period greater than one-half the period of said operation cycle, a line circuit extending between said stations, a current source at each station, means governed by said lever and including the first position of both code relays to connect said control relay and the current source at the office with said line circuit for continuously energizing said control relay because its slow release period bridges the second position periods of the code relays to maintain a given

- condition of said signalling means, and means governed by said signalling means and including the second position of both code relays to connect said indication relay and the current source 5 at the field with said line circuit to continuously energize said indication relay because its slow release period bridges the first position periods of the code relays to maintain a given position of said indicator in response to said given condition 10 of the signalling means.
13. In a remote control system, an office station and a field station, a pilot line circuit extending between said stations and serially including the windings of two code following relays one at each station, said relays each operable to a first and a second position, coding means operative to periodically open and close said circuit to operate said relays to their first and second positions in synchronism, a first and a second 15 slow release control relay as well as a signalling means having three signal relays at the field station, a manually operable controlling means having three different positions and a current source at the office station, a line circuit extending between said stations, means controlled by the code relay at the field station to alternately connect said first and second control relays to said line circuit at its first and second positions respectively, means governed by a first position of said 20 controlling means and including the first position of the code relay at the office to connect the current source with said line circuit to maintain said first control relay energized for controlling a first signal relay of the signalling 25 means, means governed by a second position of the controlling means and including the second position of the code relay at the office to connect the current source with said line circuit to maintain said second control relay energized for 30 controlling a second signal relay of the signalling means, and means governed by a third position of the controlling means to connect the current source with said line circuit to maintain both said first and second control relays energized for 35 controlling a third signal relay of the signalling means.
14. In a remote control system for railways having a stretch formed into three track sections one of which includes a track switch and 40 provided with signals to govern traffic over the switch, a field station adjacent the stretch and a remote office station, a pilot circuit connecting said stations and including two code following relays one at each station, a code transmitter to control the pilot circuit for operating said relays in synchronism, three indicators at the office station one for each track section, indication means at 45 the office station selectively responsive to the polarity of the current supplied thereto, a line circuit extending between said stations, a circuit network controlled by the track circuits and the field station code relay to supply to said line circuit current of a selected polarity pattern different for each of said combinations, means controlled by the office station relay to connect said indication means to said line circuit for operating the indication means according to the polarity pattern of the current supplied to the line circuit, and another circuit network controlled by said indication means to display the indicators in the combination corresponding to the combination of 50 said devices.
15. In a remote control system, an office station and a field station, a pilot circuit connecting said stations and including two code following relays one at each station, a code transmitter to code said circuit for operating the relays in synchronism, field station apparatus having three independent devices which can be arranged in any one of seven different combinations, three indicators at the office station one for each device of said apparatus, indication means at the office station selectively responsive to the 55 polarity of the current supplied thereto, a line circuit extending between said stations, a circuit network controlled by said devices and the field station relay to supply to said line circuit current of a selected polarity pattern different for each of said combinations, means controlled by the office station relay to connect said indication means to said line circuit for operating the indication means according to the polarity pattern of the current supplied to the line circuit, and another circuit network controlled by said indication means to display the indicators in the combination corresponding to the combination of 60 said devices.
16. In a remote control system for railways, a stretch of track formed with three track sections which can be occupied in any combination and each section having a track circuit, a field station adjacent the stretch and a remote office station, a pilot circuit extending between the 65 stations and including two code following relays one at each station, a code transmitter to control the pilot circuit for operating said relays in synchronism, three indicators at the office station one for each track section, indication means at the office station selectively responsive to the polarity of the current supplied thereto, a line circuit extending between said stations, a circuit network controlled by the track circuits and the field station code relay to supply to said line circuit current of a selected polarity pattern different for each combination in which the sections can be occupied, means controlled by the office station code relay to connect said indication means to said line circuit for operating the indication means according to polarity pattern of the current supplied to the line circuit, and another circuit network controlled by said indication means to display the indicators in the combination corresponding to the combination in 70 which the sections are occupied.
17. In a remote control system for railways, a stretch of track formed with three track sections which can be occupied in any combination and each provided with a track relay, a fourth relay associated with said stretch, a field station adjacent the stretch and a remote office station, a pilot circuit extending between the stations and including two code following relays one at each station, a code transmitter to code the pilot 75 circuit for operating said code relays in synchronism, four indicators at the office station one for each track section and one for said fourth relay, indication means at the office station selectively responsive to the polarity of the current

office station capable of displaying a different indication for each of said traffic conditions, a second line circuit consisting of another line wire extending between the stations and said common return wire, and means controlled jointly by said 5 relays to permit transmission over said other line circuit of different indication influences from said traffic controlled means to said other indication means.

18. In a remote control system, an office station and a field station, a pilot circuit connecting said stations and including two code following relays one at each station, a code transmitter to code said circuit for operating the relays in synchronism, field station apparatus having three independent devices which can be arranged in any one of seven different combinations, three indicators at the office station one for each device of said apparatus, indication means at the office station selectively responsive to the 20 polarity of the current supplied thereto, a line circuit extending between said stations, a circuit network controlled by said devices and the field station relay to supply to said line circuit current of a selected polarity pattern different for 25 each of said combinations, means controlled by the office station relay to connect said indication means to said line circuit for operating the indication means according to the polarity pattern of the current supplied to the line circuit, and another circuit network controlled by said indication means to display the indicators in the combination corresponding to the combination of 30 said devices.

19. In a remote control system for railways, a stretch of track formed with three track sections which can be occupied in any combination and each section having a track circuit, a field station adjacent the stretch and a remote office station, a pilot circuit extending between the 35 stations and including two code following relays one at each station, a code transmitter to control the pilot circuit for operating said relays in synchronism, three indicators at the office station one for each track section, indication means at the office station selectively responsive to the polarity of the current supplied thereto, a line circuit extending between said stations, a circuit network controlled by the track circuits and the field station code relay to supply to said line circuit current of a selected polarity pattern different for each combination in which the sections can be occupied, means controlled by the office station code relay to connect said indication means to said line circuit for operating the indication means according to polarity pattern of the current supplied to the line circuit, and another circuit network controlled by said indication means to display the indicators in the combination corresponding to the combination in 45 which the sections are occupied.

20. In a remote control system for railways, a stretch of track formed with three track sections which can be occupied in any combination and each provided with a track relay, a fourth relay associated with said stretch, a field station adjacent the stretch and a remote office station, a pilot circuit extending between the stations and including two code following relays one at each station, a code transmitter to code the pilot 50 circuit for operating said code relays in synchronism, four indicators at the office station one for each track section and one for said fourth relay, indication means at the office station selectively responsive to the polarity of the current

supplied thereto, a line circuit extending between the stations, a circuit network controlled by the track relays and said fourth relay together with the field station code relay to supply to said line circuit current of a selected polarity pattern with a different pattern for each combination in which the sections can be occupied and a special pattern for the position of said fourth relay, means controlled by the office code relay to connect said 5 indication means to said line circuit for operating the indication means according to the polarity pattern of the current supplied to the line circuit, and another circuit network controlled by the indication means to display the indicators 10 in the combination corresponding to the combination in which the sections are occupied and the position of said fourth relay.

18. In a remote control system for railways, a stretch of track formed with three track sections which can be occupied in any combination and each section having a track circuit, a field station adjacent the stretch and a remote office station, a pilot circuit extending between the stations and including two code following 15 relays one at each station, a code transmitter to control the pilot circuit for operating said relays in synchronism, three indicators at the office station one for each track section, indication means at the office station including four 20 individual units each responsive only to current of a selected polarity, a line circuit extending between said stations, a circuit network controlled by the track circuits including a plurality of paths, said paths having a particular 25 arrangement for each combination in which the sections can be occupied and each path set to supply current of selected polarity, means controlled by the code relays to connect the paths of the network and the units of the indication 30 35 means to the line circuit in synchronism to energize the units in a combination corresponding to the arrangement of the paths, and another circuit network controlled by said units for operating the indicators according to the combination 40 in which the sections are occupied.

19. In a remote control system for railways, a stretch of track formed with three sections which can be occupied in any combination and each section having a track circuit, a field station and a remote office station, a pilot circuit including two code following relays one at each station, a code transmitter operative to periodically open and close the pilot circuit to energize and deenergize said relays in step with each other, three indicators at the office station one for each track section, an indication circuit including a line wire and a common return wire extending between said stations, four loop circuits at the office station each including an indication relay and an asymmetric unit, said units of the first and the third loop circuits disposed to pass current of positive polarity and the units of the second and the fourth loop circuits disposed to pass current of negative polarity and said loop circuits all connected with the common return wire, a circuit network controlled by the track circuits including a plurality of paths each of which is disposed to supply current of selected polarity, means controlled by the code relays when energized to connect the first and second loop circuits and a first set of said paths to said line wire and when deenergized to connect the third and fourth loop circuits and a second set of the paths to said line wire to energize the indication relays 45 50 55 60 65 70 75

in a particular combination for each combination in which the track section can be occupied, and another circuit network controlled by the indication relays to operate said indicators according to the occupancy of the sections.

20. In a remote control system, a first and a second station, a pilot circuit connecting said stations and including two code following relays one at each station, a code transmitter provided with an operation cycle of a selected duration and operative to open and close said circuit once each cycle to respectively energize and deenergize said relays for one-half of each cycle, a code repeater relay at said first station controlled over a front contact of the code relay 15 and said repeater relay provided with a slow pick-up period and a slow release period each substantially equal to one-fourth the duration of said cycle, a line circuit extending between said stations, four circuit paths at said first 20 station the first and fourth of which are disposed to supply current of negative polarity and the second and third of which are disposed to supply current of positive polarity, four loop circuits at said second station the first and third 25 of which are responsive only to current of positive polarity and the second and fourth of which are responsive only to current of negative polarity, means including a front contact of the second station code relay to connect the first 30 and second loop circuits to said line circuit, means including a back contact of the code relay of the second station to connect the third and fourth loop circuits to said line circuit; means at the first station including a front contact of the code relay and a back contact of the repeater relay to connect the second path to the line circuit, a front contact of the code relay and a front contact of the repeater relay to connect the first path to the line circuit, a 35 back contact of the code relay and a front contact of the repeater relay to connect the third path to the line circuit and a back contact of the code relay and a back contact of the repeater relay to connect the fourth path to the 40 line circuit; and means at the first station operative to selectively govern said paths for controlling the second station loop circuits.

21. In a remote control system, a first and a second station, a pilot circuit connecting said 50 station and including two code following relays one at each station, a code transmitter provided with an operation cycle of a selected duration and operative to code the pilot circuit to alternately operate the relays to a first and a second position for substantially one-half of each cycle, a code repeater relay at the first station governed by the code relay and operative with the code relay to divide each cycle into substantially four equal periods, a line circuit extending between said stations, four control devices at the second station the first and third of which are responsive only to current of positive polarity and the second and fourth of which are responsible only to current of negative polarity, said first and second devices disposed to be connected to the line circuit at the first position of the second station code relay and the third and fourth devices disposed to be connected to the line circuit at the second position of the code relay, four control circuits at said first station the second and third of which are each operative to supply current of positive polarity and the first and fourth of which are each operative to supply current of negative 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960

tive polarity; means controlled by said repeater relay and the first station code relay to connect the first, second, third and fourth control circuits to the line circuit during the second, first, 5 third and fourth periods respectively of the cycle; and means for selectively conditioning the control circuit to be operative to govern said control devices.

22. In a remote control system for railways, a stretch of track formed with four sections each having a track relay, a field station adjacent the stretch and a remote office station, two code following relays one at each station, coding means having an operation cycle of a selected duration 10 and operative to synchronously energize and de-energize said relays, a code repeater relay controlled over a front contact of the field station code relay and provided with a slow pick-up period and a slow release period of substantially 15 one-fourth the duration of said operation cycle, an indication line circuit extending between the stations, four indicators at the office station one for each track section, four indication devices the first and third of which are responsive only 20 to current of positive polarity and the second and fourth of which are responsive only to current of negative polarity, said first and second devices connected to said line circuit over a front contact of the office station code relay and the third 25 and fourth devices connected to the line circuit over a back contact of the code relay, means controlled by said devices to govern the four indicators respectively, four circuit paths each including a back contact of a respective one of said 30 track relays, the first and fourth of said paths each operative to supply current of negative polarity and the second and third paths each operative to supply current of positive polarity; and means to connect the line circuit to the first 35 path over a front contact of the field station code relay and a front contact of the repeater relay, to the second path over a front contact of the code relay and a back contact of the repeater relay, to the third path over a back contact of the 40 code relay and a front contact of the repeater relay and to the fourth path over a back contact of each of the code and repeater relays.

23. In a remote control system, a first and a second station, a pilot circuit connecting said stations and including two code following relays, 50 a code transmitter having an operation cycle of a selected duration and operative to periodically open and close said circuit for synchronously operating said relays to a first and a second position for substantially one-half of each cycle respectively, a code repeater relay having a slow pick-up period and a slow release period substantially equal to one-fourth the duration of the operation cycle, said repeater relay controlled by 55 the code relay of said first station and operative with the code relay to divide the cycle into substantially four equal periods, a line circuit extending between said stations, sending apparatus at said first station having four independent conditions with a selected influence for each condition, receiving apparatus at said second station selectively responsive to the four influences, and means governed by said code relays and said repeater relay to connect said apparatuses to said line circuit for transmission of 60 any combination of the four influences.

24. In a remote control system for transmitting four continuing distinctive indications over a single circuit, a single two-wire line circuit connecting an office station and a field station; 75

means at the field station to energize the line circuit with current of negative polarity under a first condition during the first one-fourth period of an operation cycle of a selected duration, to energize the line circuit with current of positive 5 polarity under a second condition during the second one-fourth period of the cycle, to energize the line circuit with current of positive polarity under a third condition during the third one-fourth period of the cycle and to energize the 10 line circuit with current of negative polarity under a fourth condition during the fourth one-fourth period of the cycle; four indication devices at the office station the first and third of which are responsive only to current of positive polarity 15 and the second and fourth of which are responsive only to current of negative polarity, and means to connect the first and second devices to the line circuit during the first and second one-fourth periods of the cycle and to connect the 20 third and fourth devices to the line circuit during the third and fourth one-fourth periods of the cycle.

25. In a remote control system, a first and a second station, a pilot circuit connecting said 25 stations and serially including the windings of two code following relays one at each station, an asymmetric unit interposed in said circuit adjacent the relay at said second station and disposed to pass current of positive polarity only, 30 a code transmitter having a selected operation cycle and operative to supply current of positive polarity to said circuit during substantially the first one-half period of each cycle for operating said relays in synchronism, a line circuit extending between said stations, control and indication apparatus partly at each station and interrelated by the line circuit by the operation of said code relays, another relay at the second station responsive to current of negative polarity only 35 and connected with the pilot circuit outside of said asymmetric unit, and means at the first station to at times supply current of negative polarity to the pilot circuit during the second one-half period of each code cycle for operating said 40 other relay.

26. In a remote control system for railways, a stretch of track formed into several track sections with an approach section at each end of the stretch and said sections each provided with a 50 track circuit, a field station adjacent the stretch and a remote office station, a pilot circuit extending between said stations and including two code following relays one at each station, a normally deenergized code transmitter operative 55 when energized to periodically open and close said pilot circuit for operating said code relays, an indication circuit extending between said stations, means controlled by the code relays when operated to transmit over the indication circuit a distinctive indication impulse for each track section for indicating at the office station the occupancy of the track section, and approach control means governed by the track circuits of the approach sections for energizing said code transmitter in response to a train entering 60 either approach track section.

27. In a remote control apparatus, an office station and a field station, a pilot circuit extending between the two stations and including 70 two code following relays one at each station, a normally deenergized code transmitter operative when energized to periodically open and close said circuit for operating said code relays in synchronism, a control circuit extending between 75

- 5 said stations, control apparatus at the field station having a plurality of different conditions, controlling means at the office station having a position for each condition of the control apparatus, means governed by said relays when operated to selectively connect said controlling means and said control apparatus to said control circuit to establish the condition of the control apparatus corresponding to the position of the controlling means, and circuit means governed by the controlling means when operated to any of its positions for energizing said code transmitter.
- 10 28. In a remote control system, a stretch of railway track including a track switch and having a signal to govern traffic over the switch, a signal control relay, an approach locking relay normally energized over a back contact of said signal control relay and another normally closed circuit contact, a timing device effective when operated a selected time interval to complete a shunt path around said circuit contact, means including a back contact of said signal control relay and a back contact of said locking relay to operate said device, control means including a manually operable lever having a normal position and an operated position and effective when said lever is moved to its operated position to cause energization of said signal control relay, an indication lamp adjacent said lever, and indication means including a back contact of said locking relay operative when the lever is restored to its normal position for deenergizing said signal control relay while said circuit contact is open to illuminate said lamp at the completion of the selected operating time interval of said timing device.
- 15 29. In a remote control system, a stretch of railway track including a track switch and having a signal to govern traffic over the switch, a signal control relay, an approach locking relay normally energized over a back contact of said signal control relay and another normally closed circuit contact, a timing device effective when operated a selected time interval to complete a shunt path around said circuit contact, means including a back contact of said signal control relay and a back contact of said locking relay to operate said device, control circuit means including a manually operable lever having a normal position and an operated position and effective when said lever is moved to its operated position to cause energization of said signal control relay, an indication relay, a first and a second lamp controlled over a front and a back contact of said indication relay respectively for indicating energized and deenergized positions of said signal control relay respectively, and an indication circuit for energizing said indication relay and said circuit including a back contact of said locking relay so as to cause illumination of said first lamp when said lever is moved to its operated position and said signal control relay is energized and to cause illumination of said second lamp when the lever is restored to its normal position and said signal control relay is deenergized while said circuit contact is open only at the completion of the operating interval of said device.
